(57) **CLAIM**

The ornamental design for a maintenance module for fluid jetting head, as shown and described.

DESCRIPTION

FIG. 1 is a front perspective view of a maintenance module for fluid jetting head showing our new design, the broken lines being shown for illustration only and not forming a part of the claimed design;

FIG. 2 is a front view thereof;

FIG. 3 is a side view thereof

FIG. 4 is a left side view thereof; and,

FIG. 5 is a top view thereof, the bottom view being identical thereto.
